UNITED STATES PATENT OFFICE.

ALFRED CATCHPOLE, OF GENEVA, NEW YORK.

STEAM-BOILER.

1,078,187.

Specification of Letters Patent. Patented Nov. 11, 1913.

Application filed October 21, 1912. Serial No. 727,078.

To all whom it may concern:

Be it known that I, ALFRED CATCHPOLE, a citizen of the United States, residing at Geneva, in the county of Ontario and State 5 of New York, have invented certain new and useful Improvements in Steam-Boilers, of which the following is a specification.

The object of this invention is to provide an improvement in steam boilers.

10 Another object of the invention is to increase the area of surface with which the products of combustion will come in contact as they pass from the fire box to the smoke stack.

15 Another object of the invention is to provide the boiler with flues that are inclined in the direction of travel of the gases, both forward and back to the boiler.

Another object of my invention is to provide 20 in the boiler a series of water tubes projecting outwardly from the rear end thereof, said water tubes being of an improved design.

Another object of my invention is to provide 25 an improved arrangement of drafts or dampers by which a direct connection with the stack is provided from the fire box in emergencies.

These and other features of my invention 30 will be fully illustrated in the drawings, described in the specification and pointed out in the claims at the end thereof.

In the accompanying drawings, Figure 1 represents a longitudinal section of my improved boiler, the section being taken on the line 1^x—1^x of Fig. 2. Fig. 2 shows a vertical transverse section through the boiler on the line 2^x—2^x in Fig. 1. Fig. 3 is a sectional view on a large scale of the rear 35 plate of the boiler and one of the water tubes in engagement therewith. Fig. 4 is a vertical section on the line 4^x—4^x in Fig. 3. Fig. 5 is a perspective view of the water tube showing the rear end thereof. Fig. 6 is a rear elevation of the boiler mount.

In the accompanying drawings like reference numerals refer to like parts.

In the drawings reference numeral 1 indicates the boiler shell having the heads 2 50 and 3 in the opposite ends thereof. Be-

tween these heads are the two sets of flues, the one set 4 at the bottom of the boiler and the other set 5 being shown at the top of the boiler, with a large open space between these tubes at the back of the boiler, which 55 space tapers down toward the front of the boiler. This open space is made by inclining the lower set downwardly at the rear and inclining the upper set upwardly at the rear, although it is obvious that all the boiler flues 60 might be made parallel to each other if so desired. I have found however, that by inclining the flues upwardly slightly in the direction of the travel of the gases, the gases travel somewhat more freely and the draft 65 through the boiler is increased and the dead water between the flues in the boiler is decreased in volume.

This boiler may be set in any ordinary 70 housing with the fire box 6 in front thereof, from which the smoke and other products of combustion pass rearwardly under the boiler, then forward through the lower set of flues 4 into the smoke box 7, then rearward through the upper set of flues 5 into 75 the opening 8 which communicates with the stack.

At the rear end of the boiler I provide a series of water tubes 9, which tubes are shown 80 on a large scale in Fig. 3. These tubes are open at both ends and have a front end or neck 85 of reduced diameter, similar to a bottle neck. The boiler head 3 is provided with suitable openings which are threaded for the purpose of receiving the reduced ends 10 of the water tubes, which reduced ends are 85 also threaded and are screwed into place. As shown in Fig. 2, these water tubes are arranged in a horizontal line across the boiler. In small sizes of boilers where small 90 size water tubes 9 would be used, the reduced end or neck may be dispensed with and straight tubes used instead. Each of these water tubes is provided with a partition plate or diaphragm 11 to facilitate the 95 circulation of water through the tube. The rear end of each of the water tubes 9 is closed by a screw plug 12, the plug and water tube being suitably threaded so that the parts will go together. The plug 12 is 100

provided with the socket 13, so that it may be turned by a male wrench. Each of the plugs is also perforated to receive a water supply pipe 14, through which the supply of water is introduced into the boiler.

At the back of the boiler is provided a plate 15 which completely incloses the boiler at the rear, this plate being supplemented by a masonry structure such as is shown in Figs. 1 and 2, or the equivalent thereof. In the middle of this frame is placed the partition plate 16, which plate comes immediately back of the water tubes. The water supply pipes 14 pass through the partition plate 16, which plate is suitably perforated to receive them. The partition plate 16 is fastened to the frame 15 at each end by the machine bolts 17, 17. This partition plate, together with the water tubes 9, form the partition between the upper and lower parts of the smoke box at the rear of the boiler. Above and below the partition plate are placed the doors 18 and 19 which are hinged in the ordinary manner to the frame 15, and which can be opened to permit access to the boiler flues. At each side of the horizontal row of water tubes are provided the dampers 20 and 21. When these are open, as shown in Fig. 2, the gases and other products of combustion can pass directly from the lower to the upper part of the rear smoke box without going through the boiler flues, but when these dampers are closed the gases must pass through the boiler flues to the front smoke box and back again through the flues to the rear smoke box before getting into the stack. In order to prevent leakage through the intervals between the water tubes, bars of any desired shape, such as are indicated at 22 in Fig. 2, may be used. These bars may be wedge shaped in cross section or may be round, but in any case should extend only from the middle line of the water tubes upwardly a short distance without reaching to the top of the water tubes. On top of the tubes if so desired a sheet of metal may be laid for the purpose of more effectually closing the opening, but the tubes with the intervening bars are believed to be sufficient and would be used in all boilers except that the plate laid on top of the water tubes might be used in small boilers where small water tubes are used, in which case the intervening bars may be omitted.

Having thus described my invention, what I claim as new and patentable is as follows:

1. In a steam boiler, the combination of a shell having heads on the opposite ends thereof and smoke boxes at each end of the boiler, an upper and lower set of flues extending between said heads of the boiler, said lower set of flues being inclined upwardly toward the front of the boiler, said

boiler having a large water space between the bottom and the front end of said flues, said upper set of flues being inclined upwardly toward the rear of the boiler, a partition arranged across the head of the boiler at the rear and extending outwardly therefrom, said partition separating the lower part of the smoke box from the upper part of the smoke box, said partition being composed of water tubes arranged in a single row, said tubes being connected to the head between the upper and lower sets of flues and being placed practically in contact with each other and forming practically a solid partition.

2. In a steam boiler, the combination of a shell having heads on the opposite ends thereof, a smoke box at each end of the boiler, a partition of water tubes extending horizontally across the smoke box at the rear end of the boiler, and a damper at one end of said partition.

3. In a steam boiler having a head and a smoke box, adjacent thereto, a series of water tubes extending from said head into said smoke box and opening into the interior of the boiler, said tubes being arranged in a single row and being placed adjacent to each other so as to form a practically close partition between the upper and lower part of the smoke box.

4. In a steam boiler, the combination of a head, a series of water tubes connected to and extending through said head, each of said tubes having a cylindrical body, a shoulder at one end thereof and a reduced neck on said shoulder, said necks extending through the head and holding said tubes in a substantially solid partition.

5. A water tube for a boiler having a cylindrical body, a shoulder at one end thereof and a reduced neck on said shoulder, a partition extending through said neck and part way into the body of the tube.

6. A water tube for a boiler having a cylindrical body, a shoulder at one end thereof and a reduced neck on said shoulder, a partition extending through said neck and part way into the body of the tube, a device for closing the rear end of the water tube, a feed water pipe extending through said closing device into the bottom of the water tube.

7. In a steam boiler the combination of a head, a row of water tubes each tube thereof extending through said head and rearwardly therefrom said tubes forming a substantially closed partition, a set of flues above said tubes and a set of flues below said tubes, said flues being connected to openings in said head above and below said tubes, and extending in the opposite direction therefrom.

8. In a steam boiler the combination of a

head, a smoke box adjacent thereto, a partition extending rearwardly from the head across said smoke box, flues extending through the head and forwardly therefrom both above and below said partition, a frame work at the rear of the smoke box having a middle rail therein placed in contact with ends of said water tubes, openings in said

frame work above and below said rail, doors for closing said opening. 10

In testimony whereof I affix my signature in presence of two witnesses.

ALFRED CATCHPOLE.
